UNITED STATES PATENT OFFICE.

FRANK W. TURNER, OF KANSAS CITY, MISSOURI, MARSHALL LEFFLER, OF KANSAS CITY, KANSAS, AND CLARK DOUGLAS, OF KANSAS CITY, MISSOURI.

LAMP-SOCKET.

1,293,989.

Specification of Letters Patent. Patented Feb. 11, 1919.

Application filed November 6, 1916. Serial No. 129,707.

To all whom it may concern:

Be it known that we, FRANK W. TURNER, a citizen of the United States, residing at Kansas City, in the county of Jackson and 5 State of Missouri, MARSHALL LEFFLER, a citizen of the United States, residing at Kansas City, in the county of Wyandotte and State of Kansas, and CLARK DOUGLAS, a citizen of the United States, residing at Kansas City, 10 in the county of Jackson and State of Missouri, have invented certain new and useful Improvements in Lamp-Sockets; and we do declare the following to be a full, clear, and exact description of the invention, such 15 as will enable others skilled in the art to which it appertains to make and use the same, reference being had to the accompanying drawings, and to the letters and figures of reference marked thereon, which form a 20 part of this specification.

Our invention relates to a socket switch for incandescent lamps and has for its principal object to provide switch mechanism for closing or breaking an electric circuit 25 through a lamp, which may be operated either by a pull chain or by the ordinary switch key.

In accomplishing this object we have provided improved details of structure, the preferred forms of which are illustrated in the accompanying drawings, wherein:

Figure I is a side view of a lamp socket provided with a switch constructed according to our invention.

Fig. II is a sectional view through the socket, disclosing the switch mechanism.

Fig. III is a vertical section on the line III—III, Fig. II.

Fig. IV is a horizontal section on the line IV—IV, Fig. III.

Fig. V is an enlarged perspective view of the switch mechanism.

Fig. VI is a perspective view of the outer end of the switch sleeve and turn button.

Referring more in detail to the drawings:

1 designates a lamp socket of the ordinary type comprising a tubular body portion 2, having an indrawn neck 3 containing a threaded sleeve 4; the latter being separated 50 from the outer casing by an interior socket lining 5 of any suitable insulating material and threaded to receive the threaded metallic lined base 6 of a lamp bulb 7.

Seated tightly over the upper end of the

socket is a cap 8 having a central opening 55 9 for receiving the circuit wires 10—11 which lead from an electrical supply source through the switch mechanism, later described, to illuminate the bulb.

Located within the upper portion of the socket casing is a ring 12, preferably of hard rubber or non-conductive fiber and mounted at opposite diametrical points thereon are plates 14—15 carrying binding posts 16—17 whereby the circuit wires 10—11 are attached thereto; the plate 15 terminating at its lower end in a downwardly and inwardly extended arm 18, which is adapted to engage the central contact point 19 of the bulb 6, while the plate 14 has electrical connection, through the switch mechanism, with the metallic sleeve 4 and base collar 5, to complete the circuit through the bulb filament.

Supported within the ring is a bracket 20 75 comprising vertical end portions 21—22 and a cross plate 23, and mounted on the end plate 21 is an insulation block 25 having a central opening 26 which registers with a like opening 27 in the plate 21, and slidably and revolvably extended through the said openings is a sleeve 28. Also mounted on the block 25 and lying flush with the surface thereof at opposite diametrical points are contact plates 29—30; the plate 29 connecting at its outer end with the plate 14 and plate 30 having electrical connection with the socket collar 5.

Revolute about the sleeve 28 and seated against the block 25 is a collar 31 having 90 arms 32—33 extending laterally in opposite direction therefrom at opposite peripheral points, which are adapted, when the collar is revolved on the sleeve, to simultaneously ride over the plates 29—30 to close a circuit through the switch, and also being adapted to simultaneously seat in stop notches 34 intermediate the contact plates to prevent a retrograde movement of the collar.

Extending forwardly from opposite peripheral points of the collar 31 are fingers 35—35' which are adapted for slidable movement through slots 36—37 at opposite ends of a plate 38 which is attached transversely across the end of the sleeve 28; this arrangement being provided in order to permit slidabile movement of the sleeve within the insulation block 25, and at the same time to

hold the collar and sleeve in the same relative positions.

Revolutely mounted by means of a hub 39 that extends through the end standard 22 5 is a spiral plate 40 constituting an anchor for the sleeve having its free outer end slideable through a slot 41 in the plate 38 and extended into the sleeve 28.

Mounted on the inner end of the hub 39 10 between the standard 22 and a downturned end 22' thereof, is a ratchet wheel 42 having teeth 43 which are adapted to contact a tooth 44 turned inwardly from the plate 22; the plates 22-22' being spaced sufficiently to allow the wheel 42 to seat against or to be moved inwardly and disengaged from the tooth 44 to allow the spiral shaft to revolve on the hub 39.

Attached to the outer end of the sleeve 28 and extending through a neck 45 in the socket casing is a switch chain 46 whereby the sleeve may be drawn outwardly against the tension of a spring 47 to operate the switch mechanism; the said spring bearing 25 against the plate 38 and collar 31 to yieldingly hold the collar against the block 25 and to return the sleeve to its inner limit after an operation of the switch.

When the parts are so arranged it will be 30 seen that as the sleeve 28 is drawn outwardly by the chain the plate 38 riding along the spiral shaft 40 will draw the ratchet wheel 42 into contact with the tooth 44 to prevent rotation of the spiral shaft 35 and cause the sleeve to rotate and, due to the slideable contact of the plate 38 with the fingers 35-35', will cause a like rotation of the collar 31 to break or close a circuit through the plates 29-30.

40 Assuming that a circuit is closed through the switch and the sleeve is in its inner position as shown in Fig. II, to break the circuit through the switch an operator, by means of the chain 46, draws the sleeve 45 28 outwardly. This causes the sleeve to be rotated on the spiral shaft during its outward travel, the spiral being arranged to give the sleeve a one-quarter revolution at each operation.

50 As the sleeve rotates, the collar is likewise carried through a one-quarter revolution to disconnect the switch plates and the circuit therethrough is broken.

When the chain is released the sleeve 55 is carried back to its normal position by the pressure of the spring 47. As the sleeve is moved back retrograde movement of the switch is prevented by the seating of the switch arms in stop notches 34 in the block 60 face between the contact plates, but the spiral shaft is permitted to revolve, due to the play provided between the end standards 22-22' which allows the ratchet wheel 42 to unseat itself from the tooth 44 as the 65 sleeve returns.

In order also that the switch may be operated with a turn button, we provide the outer end of the sleeve with a slot 50 for receiving the shank 51 of a button 52 which may be turned by an operator to revolve the 70 sleeve and cause an operation of the switch the same as would otherwise be accomplished by pulling the switch chain.

By so constructing the switch it will be seen that a circuit may pass from the wire 75 10 plates 14, 29, switch collar 31, plate 30 to the bulb base 5 and after passing through the bulb filament will return from the post 19, arm 18, plate 15, and wire 11, and that the collar 31 may be rotated either by the 80 chain or turn button to break the contact through the switch parts.

Having thus described our invention what we claim as new therein and desire to secure by Letters-Patent, is:—

1. Circuit making and breaking mechanism comprising relatively fixed and movable contact members, a longitudinally movable element, an anchor for said element cooperative therewith to induce rotation of 90 said element upon movement thereof along the anchor, a rotatable mounting for the movable contact members, means on the longitudinally movable element having sliding connection with the rotatable element to 95 operate the rotatable element upon movement of the longitudinally movable element and means for moving the longitudinally movable element along its anchor.

2. Circuit making and breaking mechanism comprising relatively fixed and movable contact members, a longitudinally movable element, an anchor for said element cooperative therewith to induce rotation of 100 said element upon movement thereof along the anchor, a rotatable mounting for the movable contact members, means on the longitudinally movable element having sliding connection with the rotatable element to 105 operate the rotatable element upon movement of the longitudinally movable element, means for rotating the longitudinally movable element directly and means for moving the same along the anchor for the purpose set forth.

3. Circuit making and breaking mechanism comprising relatively fixed and movable contact members, a longitudinally movable element, an anchor for said element cooperative therewith to induce rotation of 110 120 said element upon movement thereof along the anchor, a rotatable mounting for the movable contact members, means on the longitudinally movable element having sliding connection with the rotatable element to operate the rotatable element upon movement of the longitudinally movable element, means for rotating the longitudinally movable element directly, means for moving the same along the anchor and yieldable means for 115 125 130

resisting longitudinal movement of said element and returning the same to initial position.

4. Circuit making and breaking mechanism comprising relatively fixed and movable contact members, a longitudinally movable element, an anchor for said element co-operative therewith to induce rotation of said element upon movement thereof along the anchor, a rotatable mounting for the movable contact members, means on the longitudinally movable element having sliding connection with the rotatable element to operate the rotatable element upon movement of the longitudinally movable element and means for moving the longitudinally movable element along its anchor, the said element comprising a receiving portion for a removable handle, and a handle co-operative with the receiving portion of said element.

5. In a circuit making and breaking mechanism, fixed contact points, a spiral adapted to rotate in one direction, a longitudinally movable sleeve mounted on said spiral and adapted to rotate in a direction opposite thereto; the said sleeve being mounted on said spiral in such co-operative relation therewith as to be rotated by longitudinal move-

ment of either the sleeve or spiral, movable contact member operable with said sleeve, means for effecting longitudinal movement of the sleeve along the spiral, and means for returning said sleeve to normal position.

6. In a circuit making and breaking mechanism, fixed contact points, a longitudinally movable sleeve adapted for rotation in one direction, a collar inclosing said sleeve and slidable thereon having extended contact members adapted for simultaneously engaging or disengaging the fixed points, and having arms extending forwardly along the sleeve, a spiral coaxial with the said sleeve and adapted to rotate in an opposite direction, a plate fixed to said sleeve in co-operative relation with the spiral, and having slotted end portions for slidably receiving the collar arms, means for effecting longitudinal movement of the sleeve along the spiral to operate the movable contact points, and a spring bearing against the anchor member to return said sleeve to normal position after an operation.

In testimony whereof we affix our signatures.
